[57] CLAIM

The ornamental design for ceiling fan blade cleaning device or the like, substantially as shown and described.

DESCRIPTION

FIG. 1 is a front elevational view of the ceiling fan blade cleaning device or the like showing my new design;

FIG. 2 is a right end elevational view thereof with a corner broken away to show that the fabric covered bottom pad is tapered at the front edge to permit ease of entry of the fan blade, it being understood that the fabric covered top pad front edge is similarly tapered;

FIG. 3 is a bottom plan view thereof;

FIG. 4 is a top plan view thereof; and

FIG. 5 is an enlarged rear perspective view thereof, partially broken away and showing the wooden handle and sponge rubber handle covering, the rear edges of the fabric covered pads being substantially untapered.
